CLAIM

The ornamental design for a cosmetic product, as shown and described.

DESCRIPTION

FIG. 1 is a perspective front view of a cosmetic product, embodying the new design;

FIG. 2 is a top view of the design shown in FIG. 1;

FIG. 3 is a bottom view of the design shown in FIG. 1;

FIG. 4 is a front view of the design shown in FIG. 1;

FIG. 5 is a back view of the design shown in FIG. 1;

FIG. 6 is a left side view of the design shown in FIG. 1; and,

FIG. 7 is a right side view of the design shown in FIG. 1.

The broken lines connecting the outer solid lines of the cosmetic product represent the bounds of the claim. The remaining broken lines illustrate the environment. None of the broken lines forms part of the claimed design.
